UNITED STATES PATENT OFFICE.

WILLIAM MITTENDORF AND JOHN H. MITTENDORF, OF DAYTON, OHIO.

LIQUID-MEASURE.

SPECIFICATION forming part of Letters Patent No. 325,265, dated September 1, 1885.

Application filed April 6, 1885. (No model.)

To all whom it may concern:

Be it known that we, WILLIAM MITTENDORF and JOHN H. MITTENDORF, both citizens of the United States, and residing at Dayton, 5 in the county of Montgomery and State of Ohio, have jointly invented certain new and useful Improvements in Liquid-Measures, of which the following is a specification.

Our invention relates to that class of liquid-measures in which the liquid to be measured is drawn from the main reservoir into the measuring-can proper, and thence into the can or other vessel in which the measured liquid is to be delivered.

15 We are aware that a great variety of measuring-cans of the general type above referred to have been devised and offered to the public; but most, if not all, of these are objectionable on account of the number of stop-20 cocks or faucets used and the danger that by neglecting to properly adjust all of the faucets the liquid may be permitted to flow into the measuring-can by the inlet-pipe while it is being withdrawn therefrom by the exit-25 pipe, or the liquid may be withdrawn from the measuring-can before it has been properly filled, thus giving rise to errors. They are also objectionable for the reason that no provision is made to prevent dripping after the 30 exit-cock is closed.

The object of our invention is to provide a measuring-can which renders it impossible for the attendant to make such errors, insures accuracy of measurement, and provides against 35 dripping; and it consists in the details of construction hereinafter described and claimed.

In the drawings, Figure 1 is a side elevation of a liquid-measure embodying our invention. Fig. 2 is a front view of a portion of the same; 40 Fig. 3, a longitudinal section of a two-way cock in position to allow the liquid to flow from the reservoir into the measuring-can. Fig. 4 is a cross-section on the line 4 4 of Fig. 3; Fig. 5, a longitudinal section of the cock, 45 shown in position to allow the liquid to flow from the measuring-can to the receiving-vessel; and Fig. 6, a cross-section on the line 6 6 of Fig. 5.

A represents a reservoir, and B a measuring-can connected with A by a suitable pipe, a. In order that the attendant may readily see the height to which the liquid extends, the measuring-can is provided with a section, b, 50 of glass or other transparent material, pref-

erably of semi-tubular form, with the convex 55 surface thereof projecting from the surface of the can. Either upon or immediately adjacent to this glass section is a gage, b'. If preferred, the entire measuring-vessel may be of glass and the gage placed upon its surface. An 60 air pipe or vent, b'', connects the interior of the can B with the air, and extends slightly above the top of the reservoir A in order to prevent overflow. To prevent liability of 65 breakage, we prefer to pass this pipe through the interior of the reservoir A.

C is a cock having a spout, c, the heel c' of which constitutes a valve oscillating in a sleeve, c². In the valve portion of the spout is a port, c³, and the exterior surface of c' is 70 cut away, leaving a space, c⁴, which serves as a passage for the liquid. In the sleeve are ports c⁵ and c⁶, connecting, respectively, with the reservoir A and the measuring-can B.

The operation is as follows: The spout being in the position shown in Fig. 3, the passage c⁴ connects the ports c⁵ and c⁶, allowing the liquid to flow from the reservoir A into the measuring-can B. When a portion of the liquid is to be measured for sale or use, the 80 spout is turned to the position shown in Fig. 5, closing the passage c⁴ and opening the port c⁵, as shown in Fig. 6, allowing the liquid to flow from the measuring can through the spout into the receiving-vessel. When the gage indicates that the desired quantity has been 85 drawn off, the spout is again reversed and the liquid is again free to flow from the reservoir into the measuring-can, while the drippings are held in the spout instead of falling to the 90 floor. The ports are so placed that the passage c⁴ is entirely closed before the port c⁵ begins to open.

We claim as our invention—

In a liquid-measure, the combination of the 95 reservoir A, the measuring-can B, provided with window b and gage b', the vent b'', and pipe a, with the reversible cock C, consisting of spout c, having port c³ and passage c⁴, os- 100 cillating in the sleeve c², having ports c⁵ and c⁶, substantially as and for the purpose specified.

WILLIAM MITTENDORF.
